GRINDING OR ABRADING MACHINE

Sidney Adolph Horstmann, Bath, England

Application July 9, 1938, Serial No. 218,285
In Great Britain July 10, 1937

14 Claims. (Cl. 51—95)

This invention relates to improvements in grinding machines such as are used, for example, to produce screw threads on gauges, taps and other threaded articles by means of the action of a suitably formed grinding wheel on the work piece. The chief object of the present invention is to provide a generally improved and simplified thread grinding machine in which all backlash is avoided and in which the work head carrying the work piece to be ground is rotated in a very simple and efficient manner.

Now it will be readily appreciated that in the production of screw threads by grinding it is necessary to provide means whereby the speed at which the work head of the machine is driven may be varied from time to time, for example, to suit the various diameters of the work being produced. Heretofore such speed variation has been obtained by the use of variable speed electric motors, variable speed belt drives and/or changes of gearing. All such means are not only cumbersome and to a certain extent inefficient but, in addition, they serve only the individual function in question and do not readily adapt themselves to the simplified carrying out of the other functions of the machine. It is, therefore, an object of the present invention to provide simple and efficient means of driving the work head of a grinding machine at the desired speed, which means also lend themselves readily to the carrying out of certain other desirable or even necessary operations of the machine.

According to the principal feature of the present invention, a liquid motor, preferably of the rotary type, is employed to drive the work head, said liquid motor being supplied with liquid under pressure from a liquid supply such as a pump which is appropriately driven from the main drive of the machine or by means of a separate drive as desired.

One or more suitable valves is or are provided to control the amount of liquid supplied to the liquid motor and hence to control the rate at which the work piece is rotated.

In a thread grinding machine since it is inadvisable to disengage the lead screw nut from the lead screw when traversing the work piece back, it is most desirable to provide means whereby the direction of rotation of the work head and consequently the axial movement of the work piece may be reversed in order to bring the work piece back to its initial position after it has been traversed across the edge of the grinding wheel.

With a liquid motor drive to the work head

as above described it is possible to employ a reversible liquid motor and to provide a valve for reversing the flow of liquid to the motor, thereby reversing the direction of rotation of the work piece. Such an arrangement is quite satisfactory but it is a further object of the present invention to provide an improved method of reversing the direction of rotation of the work head which will have the advantage that the reversal can be effected without in any way altering the setting of the liquid motor normally driving the work head.

According to this feature of the present invention, a separate motor is provided for reversing the work piece, this additional motor and also the liquid motor normally driving the work head being adapted to drive the lead screw through a common differential gear, the cage of which is operatively connected to the lead screw.

The liquid motor which is employed to drive the lead screw in the forward direction drives one of the side wheels of the differential gear in one direction whilst the separate reversing motor (which may conveniently be an electric motor and is hereinafter termed the "electric motor") is adapted to rotate the other side wheel of the differential gear in the opposite direction. Normally the electric motor is switched off, in which case the lead screw is rotated in the forward direction from the cage but, when it is desired to reverse the travel of the work piece, the electric motor is switched on to rotate its side wheel of the differential gear at a speed greater than that at which the other side wheel is driven and in the reverse direction. The result is that the cage, and hence the lead screw, is driven in the reverse direction at a speed which is dependent upon the difference in speed of the two side wheels of the differential gear. As the speed at which the electric motor drives its side of the differential gear may be quite high without any ill effects (since a cut is not taken on this traverse) it follows that the work piece may be quickly returned to its initial position ready for the next cut provided the grinding wheel and the work piece have been separated prior to the electric motor coming into operation.

Furthermore, since the reversal is dependent only on the difference of speed of the two motors, it will be obvious that the liquid motor may be left running in the normal way during the reversal and that as soon as the electric motor is switched off the liquid motor will immediately take over the drive and will advance the

work piece at the predetermined speed. All need of re-setting the liquid motor after each reversal is thereby rendered unnecessary and, furthermore, it is unnecessary that the liquid motor should be of a type which is capable of being reversed.

It is convenient to include in the circuit of the electric motor a make and break switch which is only closed when the grinding wheel has been 10 fully retracted from the operative position. By this means all chance of the work piece being reversed whilst still in engagement with the grinding wheel will be avoided.

The electric motor may be started and stopped 15 by means of a manually operable switch or by means of appropriate make and break switches adapted to be operated by pre-set stops carried by the work head or any other suitable part at the ends of the traverse.

20 The liquid employed for the liquid motor is preferably oil and according to a further feature of the present invention the oil pressure obtained from the pump driving the liquid motor is also used to operate the work slide and to 25 keep a constant pressure against the lead screw.

According to a still further feature of the present invention, this oil pressure is employed not only to damp the grinding wheel slide but also to cause operation of the same as hereinafter 30 described.

This oil damping of the parts not only effectively prevents backlash but also provides adequate lubrication of the parts.

Several other novel and advantageous features 35 are provided by the present invention, these being fully described hereinafter and claimed in the appended claims.

In order that this invention may be the more clearly understood and readily carried into effect, 40 I will proceed to describe the same with reference to the accompanying drawings, which illustrate by way of example and not of limitation one convenient embodiment of the present invention, and in which:

Figure 1 is a front elevation of the complete 45 machine, and

Figure 27 is a front elevation of the head stock illustrating a device for relieving taps, and

Figure 28 is a somewhat diagrammatic plan view illustrating the setting of the machine for 30 grinding taper threads.

Figure 29 is a diagram illustrating the fluid system of the machine, and

Figure 30 shows the circuit of the electric connections.

Referring now to the drawings and more particularly to Figures 1 to 3 thereof, the thread grinding machine comprises a base 100 on top of which is mounted a bed 101, the base and bed being of substantial thickness and weight to avoid 40 any vibration whilst the machine is running. In order still further to isolate the bed 101 from any vibrations which may be transmitted thereto from the base 100, rubber or other resilient pads may be inserted between the bed and the base so that 45 there is no metal to metal contact between the parts. On one side of the base 100 is mounted the electric motor 102 which is adapted to drive a fluid pump 103 mounted on the opposite side of the base. This fluid pump 103 is adapted to supply the fluid, preferably lubricating oil, under 50 pressure for the operation of the machine. In order to maintain a constant oil pressure the pump 103 is provided with a suitable bye-pass valve 103a (Figure 29) which may be incorporated 55 in the casing of the pump and which is adapted when necessary to bye-pass the oil back to the main supply tank 104. Oil under pressure is fed from the pump 103 to the rotary fluid motor 105 which is used to drive the lead screw and to rotate 60 the work piece as will now be described.

Lead screw and work piece rotating means (Figures 4 to 9)

The slide on which the head stock and tail stock 65 are mounted comprises a circular steel or other suitable bar 106 which extends from side to side of the bed 101. At the right hand end, as shown in the drawings, the bar 106 extends into a cylinder 107, the purpose of which will be described 70 hereinafter, whilst at the left hand end as shown in the drawings the slide bar 106 passes through a large bearing 108 firmly fixed to the bed 101 into a casing 109 which houses the lead screw 110. The lead screw 110 projects into the slide bar 75

which is bored out to receive the same and on the end of the slide bar is arranged the lead screw lever and nut 111. This lead screw nut is provided with a spherical surface 112 which takes 5 into the conical or spherical end 113 of the bore in the slide bar 106 so that the lead screw and nut are self aligning with respect to the slide bar 106 and any small inaccuracies are automatically taken up. The lead screw lever and nut 111 is 10 rigidly fixed to the sine-bar lever part 111 by means of screws 115 whilst the sine-bar lever is also attached to the slide bar 106 by means of the screws 116 which, as shown in Figure 8, are capable of the necessary slight movement.

15 The head stock 117 is clamped to the slide bar 106 at the desired part by means of the clamp 118 and is provided with an outstanding lug 119 which extends out over the edge of the bed 101 and is flanked on either side by ears 20 120 which serve the purpose of causing a small bearing plate 121 on the edge of the bed to follow the movement of the head stock. The bearing plate 121 has upstanding pins 122 located between the ears 120 for this purpose. Screwing 25 through the lug 119 is an adjusting screw 122a by means of which the position of the head stock 117 on the slide bar 106 may be accurately pre-set, this screw 122a engaging with the bearing plate 121. This adjusting and setting screw 30 is particularly useful when the machine is to be used for tap relieving, as hereinafter described.

The head stock is provided with two housings 123 and 124 respectively, said housings being parallel with one another as shown in Figure 5 and spaced apart horizontally. The inner housing 123 rotatably carries a sleeve 125 in the forward end of which is fixed the head centre 126. The sleeve 125 at its forward end also carries a pinion 127 and the usual outstanding arm 128 for 40 rotatting the work piece.

The other housing 124 also rotatably houses a sleeve 129, to the forward end of which is fixed a pinion 130 gearing with the pinion 127 on the sleeve 125. The rotatable sleeve 129 is, however, 45 splined on a driving shaft 131 so that it is free to slide axially along the same.

The driving shaft 131 is connected by a spherical seating joint 132 to a driving clutch sleeve 133 (the use of the clutches will be described 50 hereinafter) which is provided with a sprocket wheel 134 which is adapted to be driven by a chain 135 from the fluid motor 105 through the special form of reversing gearing according to the present invention, which will hereinafter be described.

At its remote end the sleeve 133 is connected by means of a spherical seating joint 136 to a short shaft 137 which extends into the gear box 138.

60 The sleeve 133 is thus supported between the shafts 137 and 131, and it will be appreciated that the spherical joints 132 and 136 will ensure an adequate drive whilst compensating for any lack of alignment of the parts.

65 Inside the gear box 138 the shaft 137 is provided with a gear wheel 139 which is adapted to drive through the intermediary of the gear train 141, a gear wheel 142 which is fixed to the end of the lead screw 110 where it projects into the 70 gear casing 138. The gear train 141 and also the gear wheels 139 and 142, if desired, are interchangeable in order that the speed at which the lead screw 110 is rotated may be varied for the purpose of cutting threads of different pitch.

75 For use in cutting left-hand threads an idler

gear (not shown) may be interposed between the gears 139 and 141.

It will thus be seen that when the sprocket wheel 134 is driven the work piece will be rotated through the sleeve 133 and shaft 131 whilst the lead screw 110 will be rotated through the gearing and will cause the slide bar 106, carrying with it the head stock and work piece, to be traversed across the machine.

The sprocket 134 is driven by the fluid motor 105 so that by controlling the amount of fluid supplied to the motor the rate of rotation of the work piece and also the rate of traverse of the work piece in the machine will be simply and effectively varied.

The casing 109 in which the lead screw is disposed may, if desired, be partly filled with oil so that adequate lubrication of the lead screw 110 is secured.

Now it will be appreciated that it is often required to pick up a thread on an existing threaded piece or to reduce the effective diameter of a thread being produced. For this purpose it is, of course, necessary that the work piece should be very accurately positioned relative to the 25 grooves on the grinding wheel. With thread grinding machines as heretofore constructed this has been a matter of some considerable difficulty but with the lead screw arrangement according to the present invention it may be very easily effected. The means for securing this adjustment comprise a micrometer screw 143 controlled by the handle 144 and screwing into the end bearing 145 for the lead screw 110 in the gear box 138. The end of this screw 143 engages with a ball 146 which, in turn, engages with the end of the lead screw. It will be seen that by turning the handle 144 the whole lead screw, slide bar and head stock assembly may be moved bodily in the machine and the position of the work 30 piece accurately adjusted relative to the grinding wheel so that a thread may be picked up.

When once adjusted the screw 143 may be fixed in position by means of the clamping screw 147.

Sine-bar compensator

A sine-bar compensator for accurate adjustment of the pitch of the thread being cut is provided. Sine-bar compensators have been provided in thread grinding machines as heretofore constructed but the lead screw arrangements according to the present invention lend themselves readily to the provision of a simple and very effective construction of sine-bar compensator. This device is provided inside the casing 109 55

which is provided with a slot or opening 148 covered by a cover plate 149. Pivoted at its centre to the underside of this cover plate as at 150 is the sine-bar 151 which is of channel section and is provided towards its end with adjusting 60 screws 152 passing through the side of the cover plate. By adjustment of these screws the sine-bar may be adjusted. The arcuate slots 153 in the cover plate co-operate with pins 400 to indicate the setting of the sine-bar. The lever 111 65 carrying the lead screw nut is provided with an extension 154 carrying a ball 155 which lies in the sine-bar 151. It will be seen that by adjustment of the sine-bar and co-operation of the same with the ball 155 the work piece may be 70 arranged to lead or lag slightly on the actual pitch of the lead screw 110.

Hydraulic damping of the lead screw

It was mentioned above that the use of a fluid 75

motor which is driven by oil or the like under pressure was advantageous in connection with other operations and functions of the machine. One such additional use to which the oil under pressure may be put is the hydraulic damping of the lead screw and the work head slide and the prevention of backlash therein. It is for this purpose that the cylinder 107 above mentioned is employed. Oil under pressure is conveyed from the pump through the pipe 156 and admitted to the cylinder 107 through the port 157 so as to maintain a constant oil pressure therein. The work slide bar 106 slides in and out of this cylinder as the work is traversed and acts as a piston. At all times, however, the work slide bar 106 will be subjected axially in one direction to the pressure of the oil in the cylinder and this pressure will be transmitted through the slide bar 106 to the lead screw 110 and lever 111 to take up any backlash therein. The lead screw will always engage and only engage with one of the flanks of the thread in the lead screw nut. A further advantage is also secured by this oil damping of the slide bar in so far as the slight leakage of oil from the cylinder 107 will adequately lubricate the slide bar 106 at this bearing and will keep the same free from grinding dust and metal swarf.

30 *Reversing gear (Figures 10 to 12)*

The desirability of providing reversing gear for the lead screw drive so that the work piece can be returned to its original position after a cut has been taken without the necessity of disengaging the lead screw nut from the lead screw has been mentioned above. One way of doing this would be to use as the fluid motor 105 a reversible motor and to provide a valve by means of which the flow of fluid under pressure to the motor 105 is reversed. Whilst such an arrangement is, from some aspects, quite satisfactory (and it must be clearly understood that I do not exclude such an arrangement from the present invention but wish to cover the same), yet it has certain disadvantages. For example, such an arrangement essentially involves an alteration of the setting of the fluid control valve 105a (Figure 29) and the re-setting of the same to its original position after the reverse has been effected. It is preferred, therefore, to use the reversing gear shown in Figures 10 to 12 of the accompanying drawings which overcomes these disadvantages. This arrangement employs a separate electric motor 158 in addition to the fluid motor 105 for the purpose of reversing the work piece.

60 The chain 135 which drives the sprocket 134 passes around a sprocket 159 carried by the cage 160 of a differential gear 161. One side wheel 162 of this differential gear is driven through a worm gear 163 from the fluid motor 105 whilst the other side wheel 164 of the differential gear is driven also through a worm gear 165 from the electric motor 158, the fluid motor 105 and the electric motor 158 being suitably supported with their shafts parallel to one another on an extension of the bed 101. An adjustable end bearing 166 may be provided to prevent any end play in the spindle of the electric motor which would tend to prevent the smooth running of the worm gear 165.

70 During the cutting operation the side wheel 164 of the differential gear is stationary and so the cage 160 rotates at one half the speed of the other side wheel 162 of the differential gear

and drives the sprocket 134 through the chain 135. The speed at which the wheel 162 of the differential rotates is, of course, controlled by adjusting the liquid supply to the motor 105 and when once set to the optimum speed for any one particular type of thread to be ground may be left unaltered if desired. This side wheel 162 of the differential gear rotates continuously at the same speed whilst the machine is operating. When it is desired to reverse the work piece, 10 the grinding wheel is first retracted from the work piece in the manner hereinafter described and then the electric motor 158 is switched on to rotate the side wheel 164 of the differential gear at a higher speed than the wheel 162 and 15 in the opposite direction. The electric motor 158 uses the continuously rotating side wheel 162 as a reaction, and it will be seen that the cage 160 and hence the sprocket 134 will be driven in the reverse direction, the speed being one-half 20 the difference in speed of the two side wheels 162 and 164. As the electric motor 158 may be set to rotate the side wheel 164 at a comparatively high speed without any ill-effects, since a cut is not taken on the reverse traverse, the work piece 25 may be quickly returned to its original position without unnecessary loss of time.

Immediately the electric motor 158 is switched off the liquid motor 105 will take up the drive again through its side wheel 162 to advance the 30 work piece at the predetermined speed.

It is convenient to include in the circuit of the electric motor 158 a make and break switch which is only closed when the grinding wheel has been fully retracted from the operative position. 35 One suitable arrangement and operation of such switch will be described hereinafter, and it will be seen that by this means all chance of the work piece being reversed whilst still in engagement with the grinding wheel will be avoided. 40

Tail stock and centre (Figures 13 to 15)

The tail stock 170 is also mounted on the work head slide bar 106 and is clamped thereon by means of the clamp 171. In a like manner to the head stock the tail stock is provided with an outstanding lug 172 flanked on either side by ears 173 and the lug 172 carries an adjustable positioning screw 174 which is adapted to engage with a bearing plate 175 slidably arranged on the bed 101 of the machine, the bearing plate being provided with pins 176 which engage with the ears 173 and cause the bearing plate to follow the movement of the tail stock.

Slidably mounted in the tail stock 170 is a plunger 177 which carries at its forward end the tail stock centre 178 and which at its other end extends into an hydraulic cylinder 179 which is mounted on the tail stock. Oil under pressure is fed to the cylinder 179 from the pump 103 through the pipe 180. The plunger 177 acts as a piston in the cylinder 179 and the constant pressure of the oil in the cylinder 179 will ensure a constant loading of the tail stock which is very desirable. A two-way cock 181 is included in the pipe 180 so that when desired the pressure can be shut off from the cylinder 179 and the fluid already in the cylinder emptied through the out-flow pipe 182. A compression spring 183 is also provided within the cylinder 179 bearing on the plunger 177 so that the work piece is lightly held even when the hydraulic system is not in operation. Not only does this hydraulic actuation ensure a constant pressure on the tail stock centre and give steadiness of operation but, in 75

addition, the slight leak from the cylinder 179 around the plunger 177 will give adequate lubrication of the rod and will keep the rod free from grinding dust and metal swarf.

- 6 Hand operation of the tail stock for the purpose of inserting and removing the work is provided by means of the hand lever 184 which is pivoted in a bracket 185 on the cylinder 179 and has a rod 186 which extends through the end of the cylinder. Internally of the cylinder the rod 186 is provided with a head 187 engaging in a groove 188 in the plunger 177. It will be seen that by means of the lever 184 the tail stock may be retracted when desired.
- 10

15

Grinding wheel mounting

- Arranged from front to back of the bed 101 of the machine is the grinding wheel slide bar 189 which similarly to the work slide bar 106 is in the form of a circular bar of appropriate diameter. At the rear this slide bar 189 extends into a hydraulic cylinder 190 to which oil under pressure may be admitted through the port 191 so that the 20 slide bar acts as a piston therein. At its forward end the slide bar 189 extends into a similar hydraulic cylinder 192 to which oil under pressure may be admitted through the port 193. It will thus be seen that when oil under pressure is admitted to the cylinder 190 and not to the cylinder 192 the grinding wheel slide bar 189 and the parts carried thereby will be moved forwardly in the machine and that when oil under pressure is admitted to the cylinder 192 and not to the cylinder 190 the slide bar 189 will be similarly moved rearwardly.

- An adjustable stop screw 194 is passed through the end of the rear hydraulic cylinder 190 to limit the backward movement whilst the cylinder 192 at the front of the machine is provided with a micrometer adjusting screw 195 operated by the handle 196 and provided with a scale ring 197 so that a very accurate adjustment of the forward position of the slide bar 189 is obtained. On the forward movement of the slide bar the grinding wheel is engaged with the work piece so that by adjusting the screw 195 any desired depth of cut may be obtained. The force keeping the grinding wheel in engagement with the work piece is, it will be seen, the pressure in the cylinder 190 and as this is the constant pressure supplied by the pump 103 the grinding wheel will always engage with the work piece at a constant pressure. Furthermore, the slight leakage of oil from the cylinders will provide adequate lubrication of the slide bar as in the case of the work slide bar 106.

- Clamped to the slide bar 189 is the grinding wheel housing bracket 198 on which the grinding wheel and its associated parts are all mounted. To this end the bracket 198 is provided at its upper end with a substantial bearing 199 which is adapted to receive an extension 200 outstanding from the back of the housing 201 for the grinding wheel 202. The extension 200 is a push fit in the bearing 199 and the arrangement is such that the axis of the bearing 199 passes through the centre of the grinding wheel 202.

- The grinding wheel 202 is driven by a shaft 203 mounted in bearings 204 in a sleeve 205 which is clamped in an outer tube 305 which, in turn, is bolted to the grinding wheel housing 201. The advantage of mounting the grinding wheel 202 and sleeve 205 in the outer tube 305 is that the position of the grinding wheel may be adjusted 70 to the desired relation to the axis of the bearing

199 whatever be its width. The shaft 203 is driven by an electric motor 264 by the belt drive 265, the pulleys 206 being adjustable in order that the speed at which the grinding wheel is rotated may be varied.

The electric motor 264 is mounted at one point only at each end on rubber bushes carried in brackets 207 carried by the tube 305 and the grinding wheel housing, and a rubber or spring-loaded torque reaction rod 208 is connected 10 from a bracket 209 on the front of the sleeve housing or tube to a point near the top of the motor 264 in order to steady the same. This gives a floating suspension for the motor drive.

It will be seen that the whole of the grinding 15 wheel assembly and the electric motor is carried in the bearing 199 and this arrangement is very advantageous for setting the grinding wheel for different helix angles. For this purpose there is provided at the back of the machine a shaft 210 having at its outer end an operating handle 211 and at its inner end a worm 212 driving a pinion 213 which is carried by a shaft 214 extending forwardly of the machine in a bearing 215. At its inner end the shaft 214 is provided 20 with an arm 216 having an outstanding pin 217. The pin 217 is located in a slot 218 in an arcuate scale plate 219 bolted or otherwise secured to the sleeve 305. It will be seen that by operation of the shaft 210 the scale plate 219 may be 25 raised or lowered thus causing the whole grinding wheel assembly to swing in the bearing 199. By this means an accurate setting of the grinding wheel 202 for the desired helix angle is obtained. Once the grinding wheel has been set the extension 200 is clamped in the bearing 199 and the scale plate 219 is clamped in position by means of the bolt 291. Of course, any other means of rocking the grinding wheel assembly for the purpose of setting the helix angle may be employed without departing from the scope of the present invention.

It has been pointed out above that it is desirable to include a make-and-break switch in the circuit of the electric motor 158 driving the 45 reversing gear so that the said motor can only be switched on after the grinding wheel 202 has been fully retracted from the work piece. The movement of the grinding wheel housing bracket 198 or of the slide bar 189 may be employed 50 for this purpose in any suitable way. For example, a contact rod may be provided on the end of the slide bar 189, this rod passing out through the hydraulic cylinder 190 and being adapted to bridge a pair of contacts when the grinding wheel 55 has been fully retracted. Alternatively, the grinding wheel quadrant 198 may be linked to a switch in such a manner that the switch is only switched on when the grinding wheel has reached its fully withdrawn position.

For forming or dressing the grinding wheel it is preferred to use the method described in my co-pending British patent application No. 5212/37, according to which a preformed dressing roller with a helical thread is mounted in the work 65 piece position and pressed against the grinding wheel, the two parts being rotated at the same, or substantially the same, peripheral speed. In carrying out this method with the present machine it is convenient to switch off the electric 70 motor 264 and to screw a removable handle 220 into one of the pulleys 206 so that when the forming roller has been pressed into engagement with the grinding wheel the same may be rotated at a slow speed by hand.

Hand or automatic reversing mechanism

This mechanism is shown in Figures 23 to 26 of the accompanying drawings and comprises a hand lever 221 pivoted at 222 on the bed of the machine and extending below the pivot where it is attached to the plunger of a hydraulic reversing valve, the construction of which is shown in Figures 25 and 26, is employed to control the admission of oil under pressure to and its release from the hydraulic cylinders 190 and 192. It will be remembered that in controlling the movement of the grinding wheel assembly it is necessary to admit oil under pressure alternatively to the hydraulic cylinders 190 and 192 to allow any oil in that cylinder to which oil is not being fed to be released. This operation is effected by the hydraulic reversing valve which comprises a valve body 223 suitably mounted on the bed of the machine. Slidably mounted in the central bore of this valve body is the plunger 224 which at its forward end is connected to the hand lever 221 and which is provided with two spaced peripheral recesses 225 and 226. Oil under pressure from the pump is fed through a pipe 227 to the inlet port 228 of the valve body and spaced on either side of the inlet port 228 are two outlet ports 229 and 230. The outlet port 229 is connected to the front hydraulic cylinder 192 whilst the outlet port 230 is connected to the rear hydraulic cylinder 190.

Also bored in the valve body is an outlet passage 231 which is connected by a pipe 232 to the oil reservoir, this passage communicating with two ports 233 and 234 spaced as shown and opening on to the central bore of the valve body.

When the plunger 224 is in the position shown in Figure 26 oil under pressure will flow from the inlet port 228 round the recess 226 and out of the port 230 so that it will be fed to the rear hydraulic cylinder. At the same time the port 229 connected with the front hydraulic cylinder will be placed in communication with the outlet passage 231 through the port 233 and the recess 225 and so any oil in the front hydraulic cylinder can exhaust. The grinding wheel will, therefore, be brought into engagement with the work piece. When the plunger 224 is moved to its other position shown in Figure 25 the operation will be reversed. The rear hydraulic cylinder will be allowed to exhaust through the port 230, the recess 226, port 234 and passage 231 whilst oil under pressure will be supplied to the front hydraulic cylinder 192 through the inlet port 228, peripheral recess 225 and the port 229. The grinding wheel will thereupon be retired from the work piece. Thus it is merely necessary to move the handle 221 from one position to the other in order to control the grinding wheel.

This change-over operation may, if desired, be effected automatically at the ends of the traverse of the work piece. For this purpose a bar 235 may be pivoted to the hand lever 221, this bar extending along the front of the bed of the machine and passing through a slide or eye 236 fixed to the bearing plate 121 associated with the head stock. Mounted on the bar 235, one each side of the eye 236, are two adjustable stops 237 which are set to correspond to the desired travel of the work piece. Since the eye 236 is constrained to follow the movement of the head stock it will engage with the stops 237 just prior to the end of its traverse and in so doing will operate the hydraulic reversing valve.

It will be readily appreciated that it is desirable that the plunger shall be maintained firmly in its two extreme positions and that it should move sharply to its end position once a certain amount of movement has taken place. With this object in view a device, very similar to a "dead-centre" device, is provided according to the present invention. The bar 235 instead of being merely pivoted on the pin 500 carried by the hand lever 221 is provided with an elongated slot 501 where it passes about the pin 500. The hand lever 221 is thus capable of a certain amount of movement in one direction or the other relative to the bar 235. Mounted on the pivot 222 of the hand lever 221 is a bell crank lever 502, one arm of which extends upwards to the pin 500 and the other arm 503 extends outwardly from the side of the lever 221 and is provided with a pointed nose 504. Co-operating with the nose 504 is an arm 505 which is also provided with a pointed nose 506, the arm 505 being pivoted as at 507 on the valve casing 223. A tension spring 508 is connected between the pivot 222 and a pin 509 carried by the upper end of the arm 505 so as to keep the two noses in engagement with one another. Assume that the parts are in the position shown in Figure 23 and that the bar 235 is moving to the left. In due course the right-hand end of the slot 501 in the bar 235 engages with the pin 500 and commences to swing the hand lever in an anti-clockwise direction. In doing so it causes the upper surface of the nose 504 to ride up the under surface of the nose 506 thereby separating the lever 221 and the arm 505 and increasing the tension on the spring. This movement continues until the points of the noses meet whereupon the spring 508 comes into play to snap the lever over sharply until the pin 500 engages with the left-hand end of the elongated slot 501 and this ensures the rapid change-over of the valve plunger 224. The under surface of the nose 504 now engages with the upper surface of the nose 506 as shown in Figure 24 and the spring 508 holds the valve in its new position. In passing from the position shown in Figure 24 to the position shown in Figure 23, the reverse action takes place as will be readily appreciated.

If desired, the bar 235 may be connected to one arm of a pivoted bell crank lever 238, the other arm of which is connected to a switch 239. This switch is connected in the circuit of the reversing gear electric motor and is only switched on when the reversing valve is set to retire the grinding wheel. Similarly, when the reversing valve is set to the other position to advance the grinding wheel up to the work piece, the switch 239 will be switched off and this will form an additional safeguard to prevent the work piece being reversed whilst in engagement with the grinding wheel.

It will be appreciated that the automatic operation of the reversing valve need not be carried out by direct mechanical action from the movement of the head stock as above described. For example, the head stock or any part associated with it may be adapted to close a pair of electric contacts at each end of its traverse, these contacts being included in the circuits of solenoids adapted to operate the valve plunger 224 to move the same backwards and forwards as required. Alternatively, one of the solenoids may be replaced by a spring or any other means for securing the automatic operation of the reversing valve may obviously be employed without

departing from the scope of the present invention. Furthermore, the change-over valve may, if desired, be mounted inside the machine.

5 *Tap relief means*

The machine according to the present invention also lends itself readily to the relieving of taps as they are being ground. The tap relieving mechanism comprises a ring 240 secured to the shaft 131 of the lead screw mechanism so as to rotate therewith, said ring being provided with holes 241 into which are appropriately inserted pins 242 to correspond with the particular tap being ground. Outstanding from the right-hand ear 120 of the head stock is a pin 243 on which is pivoted an arm 244 extending out under the ring 240 so as to be engaged by the pins 242. This arm takes a bearing on the bearing plate 121 by means of the ball 245 which must be adjusted by means of the adjusting screw 246 and then clamped by means of the clamping screw 247.

Now it will be seen that as the ring rotates the pins will engage with the arm 244 and will cause the same to rock about the ball 245. Hence since the pin 243 on which the arm 244 is pivoted to the head stock is on the remote side of the ball 245 the whole head stock will be twisted to give the desired effect. The use of the circular slide bar 106 permits the head stock to move readily since it merely turns in its bearings. The setting screw 122 limits the return movement of the head stock and ensures that it will always return to the correct position. The amount of relief of the tap may obviously be varied by adjusting the adjusting screw 246.

The machine according to the present invention is furthermore readily adaptable to the grinding of taper threads since, as shown in Figure 28, it is merely necessary to twist the tail stock on the circular slide bar 106 in order to secure any desired taper.

The fluid system of the machine according to the present invention is shown in Figure 29, like references being used to indicate like parts, and Figure 30 shows the electric circuit arrangements; 250 is the switch operated by movement of the grinding wheel quadrant.

The features of the present invention may, if desired, be incorporated in an internal thread grinding machine, suitable modifications being effected in the grinding head and work holders.

Any of the known forms of coolant may be employed, the same being provided from an outside pump or by a pump on the machine as desired.

Although the present invention is more particularly intended for use in thread grinding machines, it will be obvious that it is equally applicable to the production of screw thread milling cutters and other like articles which are formed with annular grooves.

I claim:

1. In a thread grinding machine, a work-head for supporting the work piece, a slide bar carrying said work-head, a liquid motor actuating said work-head, and hydraulic means acting upon said slide-bar to unilaterally bias the same, whereby back-lash is prevented.

2. In a thread grinding machine, a work-head for supporting the work piece, a slide bar carrying said work-head, a liquid motor actuating said work-head, supporting means for said slide bar, said supporting means including a cylinder into which said slide-bar extends, the portion of the slide-bar extending into said cylinder forming a

piston, means for supplying liquid under pressure from said motor to said cylinder to act upon said piston, whereby said work-head is constantly biased in one direction and back-lash prevented.

3. The device claimed in claim 1, including a lead-screw, means connecting the latter to the said slide-bar, whereby the said biasing pressure is transmitted to the said lead-screw.

4. A thread grinding machine as claimed in claim 1, comprising a lead screw, a separate motor, a differential gear connected therewith, said gear being also connected to said liquid motor and including a cage, the latter being connected to the lead-screw, said separate motor being capable of a speed different from that of said liquid motor, whereby due to the differential gear the direction of movement of the work piece is reversible.

5. A thread grinding machine according to claim 2, which includes a pump and in which the work-head slide is in the form of a round bar, said bar extending at one end into a hydraulic cylinder to which fluid under pressure is supplied by the pump.

6. A thread grinding machine according to claim 2, in which the work-head slide bar is of circular cross-section and said work-head comprises a head-stock, the same being adjustably mounted on the said circular slide bar, means being provided for locating the radial position of the said slide bar relative to the bed of the machine.

7. The device claimed in claim 1, including a lead-screw, means connecting the latter to the said slide-bar, whereby the said biasing pressure is transmitted to the said lead-screw; said slide-bar having circular cross-section, and a lead screw nut carried by that end of the said slide bar remote from the hydraulic cylinder, said lead screw nut being engaged by the said lead screw, the latter extending into the slide whereby the fluid pressure is applied to the lead screw and nut to prevent back-lash between the same.

8. The device claimed in claim 1, including a lead-screw, means connecting the latter to the said slide-bar, whereby the said biasing pressure is transmitted to the said lead-screw and a micrometer adjustment device operatively connected to the said lead screw to move the same and said slide bar carrying the head-stock bodily in an axial direction.

9. A thread grinding machine according to claim 1, comprising a grinding wheel, a round bar slide for the said grinding wheel and hydraulic means for axially biasing said bar slide.

10. A thread grinding machine according to claim 1, which comprises a grinding wheel, a motor for driving the same, said grinding wheel and the motor therefor forming a single assembly, a round bar slide, a single bearing and a quadrant supporting said assembly being mounted on the said round bar slide.

11. A thread grinding machine according to claim 1, which comprises a grinding wheel, a motor for driving the same, said grinding wheel and the motor therefor forming a single assembly, a round bar slide, a single bearing and a quadrant supporting said assembly being mounted on the said round bar slide, and in which the grinding wheel is adjustable with respect to the axis of its bearing.

12. A thread grinding machine according to claim 1, which comprises a grinding wheel, a motor for driving the same, said grinding wheel and the motor therefor forming a single assembly,

1 round bar slide, a single bearing and a quadrant supporting said assembly being mounted on the said round bar slide, a pair of hydraulic cylinders, said round bar slide for the grinding wheel extending at each end into one of said hydraulic cylinders, fluid under pressure being admitted to one or the other of said cylinders not only to provide a hydraulic bias on the slide but also to cause movement of the slide bar and the grinding wheel carried thereby.

13. A thread grinding machine as claimed in claim 1, comprising a lead screw, a separate motor, a differential gear connected therewith, said gear being also connected to said liquid motor 15 and including a cage, the latter being connected to the lead-screw, said separate motor being capable of a speed different from that of said liquid motor, whereby due to the differential gear the direction of movement of the work piece is reversible; a circuit connection for said separate motor and a make-and-break switch disposed in the circuit of the electric motor, a grinding wheel, a bar slide supporting said grinding wheel, means for actuating said grinding wheel, said 20 bar slide for the grinding wheel being opera-

tively connected to said switch, the latter being operated by movement of the said grinding wheel slide so that the switch is only closed after the grinding wheel has been retired from the work piece whereby all possibility of the work piece being reversed whilst still engaged by the grinding wheel is avoided. 5

14. A thread grinding machine according to claim 1, which comprises a grinding wheel, a motor for driving the same, said grinding wheel and the motor therefor forming a single assembly, a round bar slide, a single bearing and a quadrant supporting said assembly being mounted on the said round bar slide, a pair of hydraulic cylinders, said round bar slide for the 15 grinding wheel extending at each end into one of said hydraulic cylinders, fluid under pressure being admitted to one or the other of said cylinders not only to provide a hydraulic bias on the slide but also to cause movement of the slide 20 bar and the grinding wheel carried thereby, and means for exhausting the fluid from one hydraulic cylinder when fluid under pressure is admitted to the other.

SIDNEY ADOLPH HORSTMANN. 25
